Patented July 17, 1917.

UNITED STATES PATENT OFFICE.

GEORGE C. JENSEN, OF OAKLAND, CALIFORNIA.

LOCK-CONTROLLED VALVE.

1,233,789.

Specification of Letters Patent. Patented July 17, 1917

Application filed February 12, 1917. Serial No. 148,089.

To all whom it may concern:

Be it known that I, GEORGE C. JENSEN, a citizen of the United States, residing at Oakland, in the county of Alameda and State of California, have invented certain new and useful Improvements in Lock-Controlled Valves, of which the following is a specification.

This invention relates to a device or 10 throttle valve for internal combustion engines and particularly to the type of valve for positioning intermediate of the motor and source of fuel, preferably in the engine manifold to enable the passage of the fuel mixture into the motor to be controlled or 15 shut off thereby.

The principal objects of the invention are to provide a valve which is capable of being locked when in closed position through 20 the operation of a lock controlled mechanism situated at a distant point; to provide a means for permanently locking the valve locking means in locked position should the controlling rod between the valve and lock 25 control mechanisms be severed in an endeavor to release the valve for movement; to provide a tubular protecting member surrounding the operating rod and having engagement with the valve casing and lock 30 controlled mechanism and to provide a means for locking said tube from detachment from said valve casing and lock controlled mechanism while the valve is in locked position.

With the above mentioned and other objects in view the invention consists in the novel construction and combination of parts hereinafter described, illustrated in the accompanying drawings, and pointed out in 40 the claim hereto appended; it being understood that various changes in the form, proportion, size and minor details of construction within the scope of the claim may be resorted to without departing from the 45 spirit or sacrificing any of the advantages of the invention.

To more fully comprehend the invention, reference is directed to the accompanying drawings, wherein,

Figure 1 is a view partly in vertical section of the preferred embodiment of my invention, and for the purposes of illustration

the valve is shown as positioned in the inlet manifold of a motor.

Fig. 2 is a sectional view taken on the line 55 2-2 of Fig. 1 viewed in the direction of the arrows.

Fig. 3 is a vertical sectional view taken on the line 3-3 Fig. 1, viewed in the direction of the arrows.

Fig. 4 is a view in side elevation partly in section illustrating the valve positioned to close the channel which it controls.

Fig. 5 is a view similar to that of Fig. 4 but with the valve positioned to connect the 65 upper portion of the channel with a source of fuel supply.

Fig. 6 is a longitudinal sectional view of the lock controlled mechanism.

Fig. 7 is a sectional view taken on the line 70 7-7 of Fig. 6 viewed in the direction of the arrows.

Referring more particularly to the several views of the drawings, wherein like characters of reference designate corresponding 75 parts, 1 indicates the inlet manifold of an internal combustion engine or motor provided with the channel 2 and branch portion 3 at the upper end, which is adapted to connect with the engine or motor cylinders.

The manifold is formed with the transversely disposed valve chamber 4 therein in which is rotatably mounted a controlling valve 5 cylindrical in cross-section and which is inserted in said chamber through 85 the removal of the end wall 6 thereof. The valve is provided at its ends with the trunnions 7 operating in bearings 8 with the opposite ends of the chamber. The ends of the trunnions 8 project beyond the ends 90 of the respective bearings and to one is secured an operating lever 9 operated from a suitable point to rotate the valve within the channel 4 and to the other are secured the stops 10 adapted to contact with the lug 95 11 and limit the rotation of the valve in either direction.

The valve is provided with a port 12 extending transversely therethrough and which is adapted when the valve is rotated to a position as in Fig. 1 to register with said channel 2 and to permit the passage of a gaseous mixture into the motor. A suitable inlet 13 is provided in the wall of the chamber

4 at one side of the channel 2 and when the valve is in the above set forth position, said inlet is closed by the valve wall 14 at one side of the port 12. The rotation of the 5 valve in the direction of the arrow, Fig. 1 to dispose the port as in dotted lines Fig. 5, positions the wall 14 to close the lower portion of the channel 2 and the port 12 in register with the inlet 13 and the upper portion 10 of the channel 2 thereby shutting off the flow of fuel mixture through the manifold and admitting fresh or uncarbureted air to be drawn into the motor to enable the motor to operate as a brake. When it 15 is desired to position the valve to cut off the supply of all air to the motor through the manifold, the same is positioned as in Fig. 4 at which time the wall 14 extends across and closes the lower portion of the channel 20 2 and the inlet 13, and prevents the supply of either carbureted or fresh air to the motor through the manifold thus preventing the operating of the motor under its own power.

25 To enable the valve to be locked in its position to close the channel 2 I provide a groove 16 in a peripheral surface of the valve as in the drawings, and rotatably mounted to coöperate with the same is a locking bolt 17 within a bore 18 which is intersected by the valve 5 as in Figs. 1, 4 and 5 of the drawings. The locking bolt is provided with an arcuate recess 19 which is of a radius equal to that of the valve 5 and when said recess is positioned as in Figs. 1 and 5 of the drawings the valve is free to rotate clear of the bolt and when 30 said valve is rotated to a position as in Fig. 4 with the groove 16 in line with the bolt 17 the bolt is capable of being rotated to position a solid portion of the same within the groove 16 and thus lock the valve from rotation when in its closed position.

The bolt is preferably operated from a 45 distant point such as the vehicle cowl or dash, not shown, and at said distant point is positioned a lock controlled mechanism, Fig. 6, preferably comprising the housing 20 within which is a key controlled barrel 50 21, adapted to be retained in locked position by the locking tumblers 22. The barrel is retained in the housing by the nut 23 and is connected at its reduced inner end 24 with the locking bolt 17 by a rigid connecting rod 25 which is of sufficient length to 55 maintain the outer end 26 of the bolt 17 slightly spaced from the end wall 27 of the bore 18, as in Figs. 1, 4 and 5 of the drawings. A protecting tube 28 incloses the rod 60 25 and the same is received at one end in an annular groove 29 surrounding the open end of the bore 18 and at its opposite end is received in a suitable annular groove surrounding the reduced end 24 of the locking 65 barrel 21. To lock the opposite ends of the

tube 28 in their coöperating grooves when the valve is in locked position thus preventing the separation of the locking mechanism from the valve rod, I provide suitable guides at each end of the tube 28 and in which are 70 positioned the respective locking pins 32 and 33 adapted to be received at their outer ends in the respective seats 34 and 35 formed respectively in the body of the housing 20 and the wall surrounding the bore 18. 75 When the valve is in its unlocked position the pins 32 and 33 rest respectively in the depressions 36 and 37 in the end 24 of the barrel and in the outer end of the bolt 17, and when the barrel 21 is rotated to lock the 80 valve from rotation the pins are caused to ride over the peripheral surface of the bolt and barrel and are positioned to lock the respective ends of the tube in their coöperating members.

85 Should an unauthorized person endeavor to rotate the bolt 17 to unlocked position by first severing the tube 28 to gain access to the rod and then severing the rod 25, the rod and bolt will become permanently locked 90 together and prevented from rotation immediately on the severing of said rod 25. This is accomplished by a suitable permanent locking plunger 38 mounted in a bore 39 which intersects the bore 18. The plunger 95 is forced outwardly into contact with the bolt 17 by a spring 40. A suitable plunger receiving aperture 40' is formed transversely of the bolt 17 and the same is adapted to lie parallel with the plunger 38 when 100 the bolt is rotated to locking position but offset therefrom a distance equal to that between the end wall 27 and the face 26. A coil spring 41 surrounding a portion of the rod 25 and interposed between the end of 105 the bolt 17 and a collar 42 forces the aperture 40' in line with the plunger 38 at such time as the rod 25 is severed while the valve is in locked position, permitting the plunger 38 to permanently lock the bolt from rotation until such time as the plunger 38 is removed from the aperture 40', this being accomplished by cutting away either end wall 110 of the bore 39. A set screw 43 maintains the plunger 38 in its retracted position during the installing of the valve in a motor and after the installation is complete the set screw is withdrawn and its receiving hole 115 is sealed in any suitable manner.

Having thus described my invention, what I claim is:

In combination with a tubular inlet manifold, a casing integral therewith, a rotatable valve in said casing and adapted for closing said manifold, a locking bolt coöperating 125 with the valve for locking the same in its closed position, releasable lock controlled mechanism situated at a distant point, a connection between said lock controlled mechanism and said bolt and capable of op- 130

eration through said lock controlled mechanism to operate said bolt, a tubular protecting member surrounding said connection and cooperating with said casing and lock controlled mechanism, and means for locking the said protecting member to said lock controlled mechanism and to said casing on the locking of said valve, whereby the discon-

necting of the parts is prevented while the valve is in locked position.

In testimony whereof I have signed my name to this specification in the presence of a subscribing witness.

GEORGE C. JENSEN.

Witness:

D. B. RICHARDS.
